UNITED STATES PATENT OFFICE.

MILTON D. WHIPPLE, OF CAMBRIDGE, MASSACHUSETTS.

HOT-AIR ENGINE.

Specification of Letters Patent No. 36,581, dated September 30, 1862.

To all whom it may concern:

Be it known that I, MILTON D. WHIPPLE, of Cambridge, in the county of Middlesex and State of Massachusetts, have invented 5 an Improved Hot-Air Engine, of which the following is a full, clear, and exact description, reference being had to the accompanying drawings, making part of this specification, in which—

10 Figure 1, is a view of the engine. Fig. 2, a vertical section through the middle of the same. Fig. 3, detail to be referred to hereafter.

15 My present invention relates to certain improvements in hot air engines. I am aware that a hot air engine has been constructed in which the air was forced through a fire in a close stove, into the working cylinder, but this necessitated the expense of a 20 separate stove, and a loss of heat.

My invention consists, first in using the lower part of the working cylinder itself as a stove or fire pot in combination with the forcing of the air from below up through 25 the fire directly against the piston. Secondly in combination with a divided cylinder a long hollow piston fitting loosely in that part of the cylinder which is exposed to the direct effect of the fire, and packed at its 30 other end which is so far removed from the action of the fire that the packing will not be destroyed by it. Thirdly, in facing the end of the piston which is in immediate contact with the fire by a disk of soapstone or 35 other analogous fire resisting material. Fourthly, in combination with a hopper and the fire pot, an automatic feed for supplying the fire intermittently with fuel while the engine is in operation and by which a uniform 40 fire may be maintained proportionate to the work of the engine, and fifthly, in an explosive valve in combination with the fire chamber.

I am aware that double doors or valves 45 have been used to pass fuel into a close fire, the outer one being closed before the inner one was opened, but this alone would not answer my purpose, which is not only to feed the fire without opening the furnace (which would stop the engine) but also to 50 make the feed proportionate to the speed of the engine.

That others skilled in the art may understand and use my invention I will proceed 55 to describe the manner in which I have carried out the same.

In the said drawings A, is the bed plate, B the cylinder which is also the furnace, being furnished at its lower end with a grate C and an ash pit D. A door E through the 60 side of the cylinder gives access to the fire space above the grate C, and another door F, opens into the ash pit D, these doors are secured and clamped tight over their openings by bars *a* and set screws *b*. The lower 65 part of the cylinder B, for a height equal to the length of stroke or as high as it is exposed to the direct action of the fire, is lined with fire bricks *k*, like an ordinary stove. An explosive safety valve G held down by 70 spring *c* commands an opening *d*, made through the side of the cylinder and its lining into the fire space, this is to guard against an explosion of gas in the cylinder when the fire is first kindled and before the 75 engine is started.

The cylinder B is divided in length into two portions, 1 and 2, which are held together by screw bolts *e*. A sheet metal belt *H*, or continuation of the cylinder is secured between and connects the two portions of the cylinder B, forming with the upper portion 2, a smooth continuous surface on the interior of the cylinder, but making a break in the external surface of the cylinder 80 which tends to present the great heat of the portion 1, of the cylinder from being communicated to the portion 2, in which the head of the piston and its packing work—whereby the destruction of the packing by 85 the heat is prevented.

The top of the cylinder B is open. A standard I, secured at 5 to each side of the cylinder rises above the top of it, they have each a slot *f* in which a cross head *K*, 95 is guided. A cross brace *g* secures together and steadies the tops of the two standards. Two piston rods S, connect the cross head *K*, to the piston L. This piston consists of a head *h*, perforated with holes 6 and a sheet metal tube *i* of sufficient length to extend down into the part 1 of the cylinder B, below the top of its fire brick lining *k*. When the piston is at the top of its stroke, the bottom of this tube is closed by a sheet 100 metal end *m*, to which is secured by a screw 7, a disk *l*, of soapstone to resist the action of the fire with which it is in direct contact. The tube *i* fits loosely in the cylinder B, and is not intended to be in contact with it, 105 but to run as close as practicable, the packing *n*, being placed around the head *h*, and

2
between it and the part 2 of the cylinder B, the packing being thus removed to a considerable distance from the fire by which it would otherwise be destroyed. The holes 5 6 in the head h , allow the escape of the air from the piston when it becomes heated. Two brackets g attached to the side of the top of the cylinder B, support the bearings of a shaft M, to which is secured a crank N, 10 a rod o, is pivoted to the end of this crank and to the cross head K. Another crank O, on the end of the shaft M, is connected by a rod p to a shorter crank P, on a shaft A, which is also supported on brackets r, 15 attached to the side of the cylinder B. The reciprocating motion of the piston L rocks the shaft M, and revolves the shaft Q, which carries at its outer end beyond the side of the cylinder B, a fly wheel R, and a cam s, 20 (dotted in Fig. 2) the office of which will be presently explained.

An air-pump U, is secured to the bed plate A, it has an inlet passage t, and an outlet passage u commanded by valves, the latter 25 passage communicating by the pipe T, with the ash pit D, beneath the fire. This pump is operated in the following manner: A rod v is pivoted at 8 to one of the arms of the wheel R, its other end is connected by a pin 30 and slot at 9, to a lever w attached to a shaft V, which has its bearings on top of two standards 10 which rise from the bed A. A crank W, is attached to the shaft V, and is connected by a rod x to the piston X, of the 35 air pump U. A small pipe y opening into the air pipe T, enters the cylinder B, above the fire grate C. This throws a small amount of air in above the fire to assist in the combustion of the gases. An exhaust 40 pipe Y, communicates by a passage z (shown dotted) with the interior of the cylinder B, immediately above the fire, it is commanded by a poppet valve a², to the stem of which is attached to one end of a bent lever b² 45 pivoted at 12, to the side of the cylinder B, the other end of this lever rests on the cam s, and is vibrated by it as the shaft Q revolves. The stem of the valve a², passes through a shoft arm c² projecting from the 50 side of the cylinder B; a coiled spring d² lifts the valve a² whenever the lever b², is allowed to vibrate by its end falling on the part 13, of the cam s which is cut away (the 55 rest of the circumference of this cam is concentric and holds the valve a² closed); this cam is so formed that the valve a² shall open immediately before the piston L, reaches the top of its stroke and remain open until the piston has descended, when it is 60 quickly closed.

I will now describe the mechanism for feeding the fuel to the fire while the engine is in operation without the necessity of opening the door E which would stop the 65 engine and allow the escape of gas. A

stout metal pipe Z, (sufficiently strong to resist the pressure of the air in the cylinder B) is supported by a clamp e² on the side of the cylinder, it is bent at 14 and enters the cylinder immediately above the fire, its 70 upper part above the bend extends up vertically and is furnished with a hopper f² in which the coal, broken small is placed; immediately below this hopper is a valve g² (shown detached in Fig. 3) with a cup or 75 recess 15 cut in it, this cup receives a charge of coal and each time the valve is revolved this charge is emptied into the pipe Z, and falls onto the fire; the valve g² revolves in a box i² which communicates with the hopper f² above and the pipe Z below but is otherwise tight; this valve is revolved by the engine in the following manner. A rod k² is pivoted at 16 to the crank O, and is pivoted at its other end to a lever l² which 80 embraces and vibrates on the stem of the valve g². A pawl m² on this lever engages with a ratchet wheel n² secured on the stem of the valve g², so that each vibration of the crank O feeds the wheel n² one notch (the 85 position of the pivot 16 may be changed to feed more rapidly) and each revolution of this wheel empties a charge of coal into the fire.

The following is the operation of this 90 engine. A fire is built on the grate C, (I prefer anthracite coal), the doors E and F, are closed and secured by the screws b; the engine is started by turning the fly-wheel R, in the direction of its arrow by 100 hand, this vibrates the shaft V, and operates the air-pump X (the stroke of the piston X may be varied by changing the position of the pivot 9, in the slot in the lever w). As the piston X descends, the 105 air is forced through the pipe T, into the ash-pit D and through the fire where it is heated and expanded in the cylinder B, forcing up the piston L, immediately before this piston reaches the end of its upward 110 stroke the exhaust valve a² opens to allow the escape of the compressed air and gases from the cylinder B through the passage z, and pipe Y; the piston L, now descends by its weight and the momentum of the 115 wheel R, the valve a² closing when the piston has reached the lower part of its stroke ready for a repetition of the operation.

The bolts e which connect the portions 1 and 2 of the cylinder B are formed with 120 shoulders to support the portion 2, or pillars may be used with bolts passing through them.

The valve G is not intended to prevent the accumulation of pressure within the cylinder B, beyond a predetermined limit and thus prevent an explosion, as in the safety valves of steam boilers, but merely to permit the escape of gas, should an explosion of gases take place in the cylinder, 130

after first lighting the fire, and before the engine is set to work, as sometimes occurs; whereby the machinery might be strained and injured, if no provision was made for 5 the escape of the gas.

What I claim is:

1. Using the lower part of the working cylinder itself as a stove or fire pot, in combination with an air pump and passage 10 for conveying and forcing the air from below up through the fire directly against the piston, substantially as described and for the purposes set forth.
2. I also claim in combination with a 15 divided cylinder a long hollow piston fitting loosely in that part of the cylinder which is exposed to the direct action of the fire, and packed at its other end which is so far removed from the direct action of the 20 fire that the packing will not be destroyed

by it substantially as set forth and described.

3. I also claim facing the end of the piston which is in immediate contact with the fire by a disk of soapstone or its equivalent 25 substantially as described.

4. I also claim in combination with a hopper and the fire pot of a hot air engine an automatic feed worked from the engine and supplying the fire intermittently with 30 fuel, substantially in the manner set forth.

5. I also claim in combination with the fire or gas chamber of a hot air engine an explosive valve G, for the purpose described.

MILTON D. WHIPPLE.
